UNITED STATES PATENT OFFICE.

EDWARD S. LEA, OF MORRISVILLE, PENNSYLVANIA, ASSIGNOR TO CARRIER ENGINEERING CORPORATION, OF NEWARK, NEW JERSEY, A CORPORATION OF NEW YORK.

APPARATUS FOR CASTING POTTERY WARE.

Application filed November 12, 1924. Serial No. 749,491.

To all whom it may concern:

Be it known that I, EDWARD S. LEA, a citizen of the United States, residing at Morrisville, in the county of Bucks and State of Pennsylvania, have invented certain new and useful Improvements in Apparatus for Casting Pottery Ware; and I do hereby declare the following to be a full, clear, and exact description of the invention, such as will enable others skilled in the art to which it appertains to make and use the same.

The invention relates to apparatus for casting pottery ware from slip, more particularly relatively large pieces of sanitary ware, such, for example, as flush tanks, which are cast in porous molds with which are associated porous cores, the invention contemplating the provision of one or more matched molds and cores mounted upon a suitable portable support, preferably a suspension truck, so that the component parts of the complete mold may be assembled for the casting operations, separated for the drying and conditioning operations without separating the mold and core elements from the truck and without dissociating the individual molds and cores, so that the latter, when once suitably matched, may be used continuously until one or the other of the elements has become worn out or damaged to an extent sufficient to prevent further use. The invention further involves the pivoting of the mold bodies on the trucks on horizontal axes, so that said molds may be swung to vertical position to receive the cores and subsequently moved to inverted vertical position to permit the dumping of the castings, and the suspension of the cores above the molds, preferably by cables, which are operated by winches mounted in the frame, the parts being adjustable to secure exact registry of the cores with the molds, the winches serving to raise and lower the cores with respect to the molds and to retain the disengaged cores in suspended relation above the molds during the drying and conditioning operations.

The apparatus, as a whole, provides a relatively simple, cheap and efficient mechanism for supporting and operating the elements of the molds, including the mold bodies and the cores, during the sequential operations of pouring the slip, preliminarily

drying the castings to permit the cores to be pulled, pulling the cores, dusting the pulled cores, effecting the secondary drying of the castings in specially conditioned atmospheres to insure a uniform drying of the castings in a minimum of time, the restoration of the normal humidity of the molds, and the final reassembling of the molds and cores for subsequent casting operations, the truck-like supports being moved from station to station as the several operations are effected, thereby enabling the maintenance of ideal conditions of heat and humidity and permitting the operations to be carried out by unskilled labor and, at the same time, obviating the relatively large losses in the fabrication of pottery ware of this character by the old hand methods and operations.

The invention is illustrated in the accompanying drawings, in which:

Fig. 1 is a front elevation of a typical truck having four molds and associated cores 75 permanently mounted thereon.

Fig. 2 is an end elevation.

Fig. 3 is a plan view.

Fig. 4 is a section on line 4—4 of Fig. 1.

Fig. 5 is a perspective view of a single 80 mold and core.

Fig. 6 is a detail view of one of the clamping plates for the mold and the associated hook for locking the core in the mold.

Fig. 7 is a fragmentary sectional elevation 85 of the parts shown in Fig. 6, showing the mold and core in locked position.

Fig. 8 is a detail view of a supporting bracket for the molds.

Fig. 9 is a plan view of the same.

Fig. 10 is a section on line 10—10 of Fig. 8.

Fig. 11 is a perspective view of one of the stop brackets for limiting the swinging adjustment of the molds.

In the manufacture of pottery ware, more particularly heavy sanitary ware, by casting the same from slip, it has been customary to perform the various operations with single sets of associated molds and cores, the molds being set up on benches, the cores dropped into the molds and clamped in position, the slip poured into the individual molds, the molds and the castings then being permitted to stand in the casting position until the slip has taken its preliminary

set, to permit the cores to be drawn, after the pulling of the cores, the molds, with the castings therein, being allowed to stand until the castings are sufficiently dried to 50 permit them to be dumped, the dumping operation being manually performed by inverting the molds and allowing the castings to drop therefrom. These operations being carried out according to the best judgment 55 and skill of the individual workman, resulted in the damaging or impairment of many of the castings due to piping, balling, cracking and dunting of the castings, brought about by lack of proper and uniform 60 humidity of the mold parts and practical inability to control the drying operations, so that the castings would dry uniformly throughout, with a consequent heavy loss in the product and a heavy expense of 65 production, both in time and labor. The instant invention provides means for obviating practically all of the difficulties and uncertainties of the former hand casting operations and permits all of the sequence of 70 75 80 85 85 90 95 100 105 110 115 120 125 130 steps, from the casting of the molds with slip to and including the dumping of the partially dried castings from the molds, under ideal conditions, which results in a saving of labor and time, insures a minimum loss of castings due to imperfections and enables the casting and preliminary conditioning of the ware to be carried out continuously.

In the particular exemplification of the invention in the accompanying drawings, apparatus designed for the casting of water closet flush tank bodies is illustrated, but it will be understood that the same type of apparatus, with necessary obvious changes or modifications, may be employed for the casting of hollow pottery ware of other shapes, sizes and characteristics, without departing from the general principles of the invention.

Referring to the drawings, 1 indicates a generally rectangular frame, preferably made of channel bars, with the joints formed by electric welding, the frame being divided longitudinally at its mid section by an I-bar 2, likewise electrically welded to the frame proper. This rectangular frame constitutes the supporting truck for the molds and cores, and is supported from an overhead rail by suitable wheeled brackets or trolleys 3, which may be of any preferred form to enable the trucks to be moved from place to place in the factory or pottery, as will be understood. Secured to opposite sides of the truck frame and in horizontal alignment thereon are laterally extending brackets, preferably of the configuration shown in Figs. 8 and 9, the brackets being of general truss formation having an intermediate rib or projection 5 which fits within the channel 60 65 70 75 80 85 90 95 100 105 110 115 120 125 130 of the side member of the frame and is securely bolted to said side member. The outer ends of the brackets are formed with generally U-shaped recesses 6 to receive open ended journal boxes 7, which are adjusted vertically in the recesses 6 by means of set screws 8. Secured to the central member 2 of the truck member and in axial alignment with the brackets 4-4 is a bracket 4', generally similar to the brackets 4 except that the bearing recesses 6' in the ends thereof are not necessarily provided with adjustable journal boxes, but said recesses, in themselves, constitute journal bearings, and are extended laterally on both sides of the center member 2. These several brackets constitute the supports for four molds, which are mounted for rotation on horizontal axes in the journal bearings of the brackets, as will be explained hereinafter.

Mounted above and below the brackets 4 are pairs of brackets 10 preferably formed as castings, each having a central rib or projection adapted to fit in the channel of the side member of the frame 1 and to be bolted to said side member, each of said brackets having a suitable adjustable stop or set screw 12 mounted in the end thereof, said brackets constituting the stops or abutments to limit the swinging movement of the molds to charging and discharging position and to insure the longitudinal axes of the molds being vertical in both positions of the latter.

The mold proper, designated by reference numeral 15, is made of plaster of Paris, or similar absorbent material, and may, if desired, be of the standard form commonly employed in casting similar pieces of pottery ware by hand. In the particular form of mold illustrated, for casting flush tanks, the interior of the mold is formed to the exact configuration of the exterior of the cast tank. It is highly desirable that the entire exterior of the mold body 15 be exposed to the atmosphere to facilitate uniform drying of the casting in the mold and in order to obstruct as little of the exterior surface of the mold as possible, a special form of support for pivotally mounting the individual molds on the truck is provided, said support comprising two skeletonized frames 17 adapted to engage the lateral faces of the mold in restricted areas of contact, said frames being secured and clamped to the mold by means of four tie rods 23, which pass through perforated ears at the respective corners of the frame 17.

Each frame 17 comprises a central section reticulated and offset from the body of the mold and two openwork side sections 18, the inner faces of which conform to and bear against the outer surface of the mold, the frame being properly positioned on and held against movement relatively to the mold by lugs 19, which engage correspond-

ingly shaped recesses 19' formed in the body of the mold, as illustrated in Figs. 6 and 7. Preferably formed integrally with each of the frames 17 and centered thereon is a 5 pintle or journal 20, which engages the aligned bearings in the respective brackets 4 and 4' carried by the vertical members of the truck frame. In order to compensate for any departure from true alignment of the pintles on opposite sides of the mold supporting frame, the adjustable journal box 7 of the bracket 4 is provided. Projecting from the upper marginal edge of each of the side frames 17 is a bracket-like 10 element 21 having a laterally projecting pin 22, which serves as an attachment for a special arrangement of springs 28 for securing and holding the mold against the stops 12 on brackets 10, in both positions 15 of the mold. Pivoted at 25 on the inner face of each of the frames 17 and operating in the space between the corresponding faces of the frame and the body of the mold are cam hooks 24, which are adapted to 20 lock the core to the mold, as will be hereinafter explained.

Secured to the upper horizontal bar of the truck frame 1 are brackets 30, one mounted at approximately each end of the 25 top bar and the other at the middle of said bar, the brackets extending beyond the front and rear of the frame, each bracket having formed in its forward portion a slot 31 in which is slidably and adjustably mounted 30 a U-shaped shackle 32. Locked to the brackets 30 by the shackles 32 are shafts 33, each shaft carrying a pair of pulleys 34 which are adjustable longitudinally of the shaft by set nuts 34', or other suitable 35 devices. Engaging each of the pulleys 34 is a cable 35 having an eye or loop 36 formed in its free end, and its other end secured to a special type of winch or winding mechanism. Each winch comprises a barrel portion 37, preferably formed as a section of 40 metal pipe, journaled in one side bar and the intermediate bar of the truck frame 1. The end of each cable 35 is secured to the corresponding end of its winch by a special 45 form of adjustable clamp 38, comprising a split collar having interior grooves on one face to clamp the end of the cable firmly between the parts of the collar, the collar being locked to the barrel 37 of the winch 50 by bolts 38'. In order to adjust the length of a given cable, it is necessary only to ease off the nuts of bolts 38' slightly, to permit the clamping collar to be rotated on the barrel 37 by tapping the collar with a hammer or the like, and after the adjustment 55 has been effected, the bolts 38' are again set up to firmly clamp the collar in position. Each winch barrel is provided with a ratchet 39 having a hub which slips over 60 the end of the barrel and is keyed thereto

by a pin 40 which passes diametrically through the barrel and also constitutes means for engaging the slotted end of a removable crank by which the winch is rotated. In order to lock the ratchets 39, 70 a simple form of loose pawl 41 is dropped between the outer face of the ratchet and the bottom of the channel iron forming the vertical side member of the frame 1, as illustrated in Figs. 1 and 2, the pawl being 75 lifted readily by the operator to disengage the ratchet, when the corresponding winch is to be operated to pay off the cables 35.

The cores 50, like the mold bodies, are made of plaster of Paris, or similar absorbent material, and, in the type of machine illustrated, are fashioned to form the interior of a flush tank, the particular core being standard for this specific type of work. The core is hollow and, when assembled with the mold 15, provides a maximum surface for the evaporation of water absorbed from the casting. The upper portion of each core is a relatively heavy flange surrounding the core and serving as the seat for engaging 80 the upper rim of the mold. The individual cores 50 are suspended from the corresponding pairs of cables 35, which run over the pulleys 34, the connection between the core and the pulley being effected by a rod 51 running transversely through the top flange section of the core, which is provided with aligned openings 52 to receive the rod, the ends of which latter project beyond the sides 85 of the core and are engaged by the loops 36 on the ends of the cables, said rod also affording abutments to be engaged by the hooks 24 to lock the core to the mold, as illustrated in Fig. 5 and in dotted lines in 90 Fig. 2. Preferably the outer portions of the openings 52 in the core, which receive the rod 51, are chamfered or countersunk so that any bending strains on the projecting 95 ends of the rod will not tend to split the friable material of the core adjacent the 100 holes 52.

While the apparatus as described is adapted to the hand pouring of the slip, it lends itself with particular facility and economy to the simultaneous pouring of the slip into the several molds by a special construction of valved supply pipes, at a definite pouring station, as described in my copending application, Serial No. 749,490, filed of even date herewith, in which the same type of carriage is more or less diagrammatically illustrated as a component of the plant and the method of casting, as described and claimed in said application aforesaid.

From the foregoing description, it will be apparent that the mold bodies and cores may be readily assembled in proper relation on the supporting trucks by unskilled labor, as the adjustments are few and simple, involving the leveling of the trunnions 20 to bring 125 130

the tops of the molds in the horizontal position and the longitudinal axis in exact vertical relation, the leveling being effected by adjusting the single journal box 7 by means of the set screw 8, as explained. The maintenance of the molds in proper vertical position in both the charging and dumping relations is effected by the adjustable set screws 12 in the ends of the brackets 10. In order 10 to hold the molds in vertical position during the pouring, drying and dumping operations, the springs 28 are provided, the latter being fastened to the side members of the truck frame 28, all of said springs having 15 eyes or hooks at their ends to be engaged over the laterally projecting pins 22 on the outer supporting frame of the mold.

A special advantage of this structural form of mold supporting truck, is that it 20 may be made up of stock forms of channel irons and relatively rough castings which require no special machining, except in the parts which are in rubbing engagement, as, for example, the journals, bearings and the 25 faces of the pulleys. The trucks being suspended from overhead trackways may be moved from point to point in the pottery, where the various operations may be performed by unskilled labor with the assurance 30 of a minimum of defective castings, by reason of the fact that the initially matched molds and cores are never dissociated until one or the other is damaged beyond repair and, when the associated molds and cores 35 have been properly adjusted on the trucks, derangement of the adjustment is practically impossible, but, when readjustment is found necessary, it may be effected quickly and at a minimum of effort and expense, 40 both in respect of the adjustment of the molds and the adjustment of the cores relatively to the latter.

What I claim is:

1. Apparatus for casting pottery ware 45 from slip comprising a portable support, a mold pivoted thereon for rotary movement from charging to dumping position, and a core suspended on said support above the mold and adapted to be moved into and out 50 of cooperative engagement with the latter.

2. Apparatus for casting pottery ware 55 from slip comprising a portable support, a mold pivoted thereon for rotary movement from charging to dumping position, means for adjusting the axis of rotation, a core suspended on said support above the mold and adapted to be moved into and out of cooperative engagement with the latter, and means for adjusting the suspension devices 60 to effect registry of the core with the mold.

3. Apparatus for casting pottery ware 65 from slip comprising a portable support, a mold journaled on a horizontal axis in said support, means to retain the mold vertical in charging and dumping positions, and a

core suspended on said support above the mold and adapted to be moved into and out of cooperative engagement with the latter.

4. Apparatus for casting pottery ware 70 from slip comprising a portable support, a mold pivoted thereon for rotary movement from charging to dumping position, means for adjusting the axis of rotation, and a core suspended on said support above the mold and adapted to be moved into and 75 out of cooperative engagement with the latter.

5. Apparatus for casting pottery ware 80 from slip comprising a portable support, a mold pivoted thereon for rotary movement from charging to dumping position, means for adjusting the axis of rotation, a core suspended on said support above the mold and adapted to be moved into and out of 85 cooperative engagement with the latter, and means for locking the core to the mold.

6. Apparatus for casting pottery ware 90 comprising a truck, a mold pivoted on a horizontal axis on said truck, and a core suspended on said truck and adapted to be moved by the suspending means into and out of cooperative engagement with the mold.

7. Apparatus for casting pottery ware 95 from slip comprising a portable support, a mold pivoted thereon for rotary movement from charging to dumping position, a core cooperating with said mold, and means connecting the core with the support for raising and lowering the core relatively to the 100 mold.

8. Apparatus for casting pottery ware 105 from slip comprising a portable support, a mold pivoted thereon for rotary movement from charging to dumping position, a core cooperating with said mold, cables for suspending the core vertically above the opening in the mold, and means for operating the cables to lower and lift the core relatively to the mold.

9. Apparatus for casting pottery ware 115 from slip comprising a truck including a substantially rectangular frame having a wheeled suspension from an overhead trackway, laterally extending brackets from the side bars of said frame having relatively adjustable journal bearings, a mold having aligned lateral journals engaging said bearings, laterally extending brackets at the top of said frame, a shaft secured to said brackets and adjustable longitudinally of the latter, pulleys rotatable on and adjustable longitudinally on said shaft, cables operating over said pulleys, means on the frames for actuating the cables, and a core suspended from the free ends of said cables.

10. Apparatus for casting pottery ware 120 from slip comprising a truck including a substantially rectangular frame having a wheeled suspension from an overhead track- 125

- way, laterally extending brackets from the side bars of said frame having relatively adjustable journal bearings, a mold having aligned lateral journals engaging said bearings, laterally extending brackets at the top of said frame, a shaft secured to said brackets and adjustable longitudinally of the latter, pulleys rotatable on and adjustable longitudinally of said shaft, cables operating over said pulleys, means on the frame for actuating the said cables, a core suspended from the free ends of said cables, and means for locking the core to the mold when said parts are in charging position.
11. Apparatus for casting pottery ware from slip comprising a truck including a substantially rectangular frame having a wheeled suspension from an overhead track-way, laterally extending brackets from the side bars of said frame having relatively adjustable journal bearings, a mold having aligned lateral journals engaging said bearings, laterally extending brackets at the top of said frame, a shaft secured to said brackets and adjustable longitudinally of the latter, pulleys rotatable on and adjustable longitudinally of said shaft, cables operating over said pulleys, winch mechanism on the frame for actuating the cables, and a core suspended from the free ends of said cables.
12. Apparatus for casting pottery ware from slip comprising a hollow mold of porous material, and means for pivotally supporting said mold on a horizontal axis, including skeleton frames engaging the ends of the mold in restricted areas and provided with lateral journals, and tie rods connecting said frames.
13. Apparatus for casting pottery ware from slip comprising a hollow mold of porous material, and means for pivotally supporting said mold on a horizontal axis, including skeleton frames engaging the ends of the mold in restricted areas and provided with lateral journals, said frames having lugs thereon engaging holes in the body of the mold, and tie rods connecting said frames.
14. Apparatus for casting pottery ware from slip comprising a hollow mold of porous material, skeleton frames provided with journals engaging the ends of the molds, tie rods connecting said frames and clamping the same to the mold, a core cooperating with said hollow mold, a rod passing through the top part of the core, hooks on said frame to engage the ends of the rod to lock the core to the mold, means for supporting the mold on said journals to permit rotation of the mold from charging to dumping position, and means for engaging and disengaging the core and mold and for suspending the core above the mold.
15. Apparatus for casting pottery ware from slip comprising a substantially rectangular frame, a series of molds pivotally mounted for rotation on horizontal axes on opposite sides of the frame, a corresponding series of cores adjustably suspended from said frame to register with said molds, and means for operating the suspending means to engage and disengage the cores and the molds.
16. Apparatus for casting pottery ware from slip comprising a substantially rectangular frame, a series of molds pivotally mounted for rotation on horizontal axes on opposite sides of the frame, a corresponding series of cores, cables suspending the cores from the frame to register with the molds, and winches mounted on the frame for operating the cables to engage and disengage the cores and molds.
17. Apparatus for casting pottery ware from slip comprising a substantially rectangular frame, a series of molds pivotally mounted for rotation on horizontal axes on opposite sides of the frame, means for leveling the molds, a corresponding series of cores, cables suspending the cores from the frame to register with the molds, and winches mounted on the frame for operating the cables to engage and disengage the cores and molds.
18. Apparatus for casting pottery ware from slip comprising a substantially rectangular frame, a series of molds pivotally mounted for rotation on horizontal axes on opposite sides of the frame, means for leveling the molds, stops on the frame for arresting the molds in vertical relation in charging and dumping positions, a corresponding series of cores, shafts mounted adjacent the top and transversely of the frame and adjustable toward and from the frame, pulleys journaled on and adjustable longitudinally of the shafts, cables running over the pulleys and engaging opposite sides of the corresponding cores, and winches mounted on the frame for operating the cables to engage and disengage the cores and molds.

In testimony whereof I affix my signature.

EDWARD S. LEA.
